CLAIM

The ornamental design for a sofa cover for lounge chair, as shown and described.

DESCRIPTION

FIG. 1 is a top perspective view of a sofa cover for lounge chair, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view showing the sofa cover for lounge chair, in state of use;

FIG. 9 is a front perspective view showing the sofa cover for lounge chair, in another state of use and for the purpose of clarity shown in isolation; and,

FIG. 10 is an enlarged view of detail 10 in FIG. 1.

The broken lines depicting pattern on the sofa cover for lounge chair form no part of the claimed design. The broken lines depicting stitching on the sofa cover for lounge chair form no part of the claimed design. The broken lines depicting straps and other structural elements represent portions of the sofa cover for lounge chair that form no part of the claimed design. The broken lines depicting sofas in FIGS. 8 and 9 show environmental subject matter that forms no part of the claimed design.

1 Claim, 8 Drawing Sheets
